UNITED STATES PATENT OFFICE.

OTTO HEIKEL, OF JERSEY CITY, NEW JERSEY, ASSIGNOR TO THE NATIONAL ELECTRIC LIGHT AND POWER COMPANY, OF NEW YORK, N. Y.

MAGNETO-ELECTRIC MACHINE.

SPECIFICATION forming part of Letters Patent No. 268,099, dated November 28, 1882.

Application filed November 7, 1879.

To all whom it may concern:

Be it known that I, OTTO HEIKEL, of Jersey City, in the State of New Jersey, have invented an Improvement in Magneto-Electric Machines, of which the following is a specification.

In cases where the cores in a magneto-electric machine are mounted upon a revolving disk the helices surrounding such cores have usually been wound in the same direction, and hence the secondary current set up in the helices, while traveling in one direction in the entire helix, is moving in opposite directions in the wires where one helix is adjacent to another, so that there is a loss of electric energy.

The object of my present invention is to obtain a powerful secondary current in helices that are wound in the same direction, and at the same time reduce the counteracting force to the minimum amount.

I make use of a circular range of armature-cores; but these cores, instead of being cylindrical or flattened and placed with the longest diameter either radially or as chords to the circle of rotation, as has heretofore been the case, are placed with the longest diameters of the cores at an inclination or obliquely to the radial lines. This allows the greatest number of cores to be introduced, and at the same time the helices are wound in the same direction and the opposing influence of one helix and core upon the adjacent helix and core is reduced to a minimum.

In the drawings, Figure 1 is an elevation, partially in section. Fig. 2 is a transverse section at the line $x x$. Fig. 3 is a diagram of the inclined cores and helix-wires. The other figures are separately referred to hereinafter.

The shaft a is supported in journal boxes or bearings $b b$. Upon the frames $b' b'$ are the field-of-force magnets $c c$, that face each other. These may be of any desired number or character. I have, however, shown four such magnets on each frame, and the cores of these are elongated in the direction of the rotation of the armature-cores, as in Letters Patent No. 184,377, granted to me November 14, 1876. Upon the shaft a is a disk, d , with circular ranges of armature-cores $e e'$ upon opposite sides, as in Letters Patent No. 184,377 aforesaid; but the cores are elongated and are placed at an inclination to the radial line. This enables me to introduce a large number of cores,

and to have each core of a larger size than heretofore, so as to obtain the best results from the inductive action.

The helices i are wound in one direction. The diagram Fig. 3 illustrates the manner of winding. By the lines thereon and the arrows it will be seen that the currents set up in the helices travel in one direction; but near the curved edges of the armature-cores the current in one helix is moving in the other direction to the current in the adjacent helix; but the field of magnetic influence on the curved edges of the armature-cores is small, and hence the currents have but little retarding or neutralizing effect the one on the other. The wires of the helices may be connected and taken off in the well-known ways.

The commutator plates or bars h are arranged around the shaft a , and the springs or brushes k bear on such plates.

The helix of each armature-core may be wound complete, then the wire taken to a commutator-bar, and then to the commencement of the next helix, and so on all around the circular range, as in aforesaid patent; and I remark that the helices may be wound with single wires, or two or more wires may be used, so as to form sections, as in said patent, and the circuits can be taken away from the helices through commutator plates and brushes in any well-known manner; and, if desired, the circuit can be taken off from each helix to an electric light or other article to be operated by electricity, or the same may be led through the helix of the field-magnets, and the return-circuit may be through one or more common conductors, as set forth in my application filed November 14, 1878. In the arrangement of the circuits I have made an improvement over those heretofore in existence. Instead of connecting one armature-helix to the next and forming one closed circuit and connecting the same with commutator-plates and an outgoing circuit returning through one or more conductors, I connect the helix of one of the circular range of armature-cores to the helix of another armature-core occupying the same position in relation to the field-of-force magnets, so that in each group thus connected there is a rise and fall in the electric tension simultaneously. This circuit is connected to the commutator-bar, so that the current is taken

off from the helices in that group at the culminating-point, and returns either to the commutator of opposite polarity or by a common conductor, the current passing in its circuit 5 through the lamp or other article to be energized thereby.

The diagrams Figs. 4, 5, and 6 represent the circuit-connections as made according to this feature of improvement.

- 10 Fig. 4 represents the connections to the commutator corresponding to the armature-cores shown in Fig. 2. In this the helices are connected with reference to four field-magnets. The helices 20 and 21, that are at ninety degrees apart, are connected, and one end of one helix, 21, is connected with one commutator-bar, 1, and the other end of the other helix, 20, is connected to the next commutator-bar, 2, and then from 2 the wire passes to the helix 20 22 and across to helix 23, that is ninety degrees distant, and then to the commutator 3, and so on all around the range of helices. There are twenty helices and ten commutator-bars, and, there being four field-magnets, there 25 are four commutator-springs, placed so as to take off the currents at the culminating-points, or points where the flow of the secondary or induced current is strongest. By this arrangement the armature-cores are connected in a 30 complete metallic circuit; but, instead of one helix being connected to the next, the connections are between the helices that are the same distance apart as the field-of-force magnets, and hence in the same magnetic field, and 35 the rise and fall of electric tension is the same in the helices thus connected, as they enter and leave the respective magnetic fields together. This mode of grouping and connecting the helices in one closed circuit is employed at 40 the right side of the disk *d*, Fig. 1, and with commutator-springs *k* and bars *h*. On the left side of the disk *d*, Fig. 1, the armature-cores *e* and their helices correspond to those on the other side of the disk. They are flattened and 45 inclined to the radial line, as seen in Fig. 5, and the connections are between the helices that are the same distance apart (ninety degrees) as the field-magnets. The connections from the groups of helices, however, vary slightly. 50 Instead of having ten commutator-plates, I have two commutators, *w* and *x*, each of which has five plates, and there are four brushes to each. Ten of the armature-helices are connected to the commutator-plates *w* and the 55 other ten to the commutator-plates *x*, and the connections to *w* are represented in the diagram Fig. 5 in full lines and the connections to the other ten by dotted lines. Starting at a commutator-plate, (*w* or *x*), the connection 60 passes to one helix—say No. 6—thence to the helix ninety degrees distant, No. 1, and from there to a common conductor. The whole of these helices are similarly connected, and the common conductors are wires leading from the 65 respective helices to a ring, *o*, upon the shaft *a*, upon which one or more brushes bear. The circuits pass from the brushes of the commu-

tators *w* and *x* to electric lights or other devices acted upon by electricity and return to the common conductor *o*.

The diagram Fig. 6 illustrates one circuit, the current set up in the armature-helices passing from the commutator *w*, by one of the brushes, to an electric light, *l*, and returning through the brush and ring *o* to the other end of the two helices *i* that are connected. In Fig. 10 I have represented twenty-four helices, with the connections of the helices that are ninety degrees apart, so as to be adapted to four field-magnets. Twelve of these helices are connected to the six plates of one commutator, and the intermediate helices are to be connected to a second commutator. The opposite ends of the helix-wires are to pass to a common conductor, as aforesaid. In the diagram 85 Fig. 11 there are twenty-eight helices, similarly connected to seven plates in each commutator. In Fig. 12 the twenty helices are represented as joined in pairs, and one end of each pair of helix-wires passes to a commutator-plate, and the other end is to go to a common conductor, the helices of the pairs being ninety degrees apart, so as to act with four field-magnets.

In order to avoid sparks at the commutator, 95 I introduce a resistance, *r*, in each circuit. It may be a rheostat at the ring *o*, serving for all the circuits, or it may be a resistance in the conductor in the shunt or branch, as at *r*, Fig. 6, the same maintaining a metallic route for the current when interrupted at the commutator, so as to prevent a spark. If the helices are wound in sections around the armature-cores, the number of commutator-plates will be increased in proportion, and in cases where 105 the field-of-force magnets are increased in number the distance between the helices that are connected will be varied.

In Fig. 7 the connections are illustrated for four field-magnets, eight armature-cores, and 110 two helices on each armature-core. In this instance the end *s* of each pair of helices pass to the common conductor *o*. Fig. 8 shows the same number of armature cores and helices and the connections to the commutator; but 115 the ends of the pairs of helices are all connected to the commutator-plates, so as to form a closed circuit all around between the armature-helices. In Fig. 9 the connections are the same as those shown in Fig. 5, but the 120 helices are wound upon a ring-shaped armature-core instead of separate armature-cores. There are four field-magnets in this case, and the connections cross between helices that are ninety degrees apart. In the diagram Fig. 13 125 the circuit-connections are represented as passing from one pair of helices to the commutator-blocks of different commutators, thence through the brush and circuit-wire to a light, and returning by the brush of the other commutator. Fig. 14 represents the elliptical core of the magnet shown in my Patent No. 184,377, with the addition of a plate across the end, extending at each side of the core and

tapering toward one or both ends, so as to cause the rise and fall of tension to be gradual.

I am aware that two or more helices have been connected together. Where these connections are made, as in English Patent No. 4,905 of 1876, there is a lack of uniformity all around in the connections. In my improvement I do not connect the adjacent helices to adjacent commutator-plates; but one or more helices intervene between the connections to adjacent commutator-plates, so as to admit of coupling up the helices in one or more pairs in a group all around the circular range of helices, and thereby obtaining perfect uniformity in the connections that unite the helices in pairs.

I am also aware that a resistance has been placed between the armature-helices and the field-magnet helices to allow for a constant current through the field helices. In my improvement I do not employ any such resistance; but I place a resistance in a shunt in the circuits of the armature-helices only for lessening the spark at the commutator.

I do not claim a fine metallic wire introduced between the helices in a magnetic motor, as the same has been used.

I claim as my invention—

1. The combination, in a magneto-electric machine, of a circular range of elongated cores and helices placed at an inclination to each other, with the portions of the helices where the wires are bent the most suddenly adjacent to each other, so that the retarding effects of the currents traveling in opposite directions may be reduced to a minimum, substantially as specified.

2. In a magneto-electric machine, a circular range of armature-helices connected up uniformly in groups in a continuous circuit and to commutator-plates, the wire from one commutator-plate passing to one helix, then to the second or more distant helix, and directly back to the commutator-plate next to the first one, and so on all around the whole circular range of uniform groups, substantially as set forth.

3. The combination, in a magneto-electric machine, of field-of-force magnets, armature cores and helices, connections from the armature-helices to commutators, and a shunt-circuit containing a resistance and independent of the circuit passing through the commutators, for the purposes set forth.

4. In a magneto-electric machine, a circular range of armature-helices connected up uniformly in pairs, and one wire of each pair of helices connected to a commutator-plate and the other wire connected in a return-circuit, substantially as set forth.

5. An elliptical core for the electro-magnet, with a plate across the end, extending at each side of the core and tapered, substantially as set forth.

Signed by me this 3d day of November, A. D., 1879.

OTTO HEIKEL.
